ATTY.

UNITED STATES PATENT OFFICE.

MARTIN V. HAMMACK, OF PROVIDENCE, RHODE ISLAND.

DESIGN FOR A BADGE-PIN.

SPECIFICATION forming part of Design No. 26,015, dated September 15, 1896.

Application filed July 31, 1896. Serial No. 601,265. Term of patent 34 years.

To all whom it may concern:

Be it known that I, MARTIN V. HAMMACK, a citizen of the United States, residing at Providence, in the State of Rhode Island, 5 have invented and produced a new and original Design for Badge-Pins, of which the following is a specification, reference being made to the accompanying drawings, showing a part thereof.

10 Figures 1 and 2 are top views of a badge-pin, showing my design; and Figs. 3 and 4 are side views of the same.

The leading features of my design consist

in the representation of a bird having in its bill a bug or beetle.

15 In the drawings, A represents the body of the bird; B B, the wings, which may be either spread or closed; C, the head, with the bill D, in which is held a bug or beetle E.

What I claim is—

20 The design for a badge-pin herein shown and described.

MARTIN V. HAMMACK.
